COMBINED OIL DRAINING AND STORAGE SERVICE UNIT

Linus E. Russell, Springfield, Ohio, assignor to Peters &
Russell, Inc., Springfield, Ohio, a corporation of Ohio

Filed Aug. 23, 1961, Ser. No. 66,475

Term of patent 14 years

(Cl. D52—2)

FIG. 1 is a front perspective view of a combined oil draining and storage service unit embodying my new design;

FIG. 2 is a rear perspective view thereof.

The undisclosed side of the service unit is substantially the same in appearance as the side shown. The essential features of the design reside in the portions shown in full lines.

I claim:

The ornamental design for a combined oil draining and storage service unit, substantially as shown and described.
